US00D536857S

(12) **United States Design Patent** (10) Patent No.: **US D536,857 S**
Schuller et al. (45) Date of Patent: **** Feb. 20, 2007**

(54) **IMPLEMENT FOR CONTACTING SURFACES**

(75) Inventors: **David William Schuller**, Lebanon, OH (US); **Craig Merillat Rasmussen**, Loveland, OH (US); **Brent William Mason**, West Chester, OH (US); **Anthony Piazza**, Palo Alto, CA (US); **Sally Madsen**, Mountain View, CA (US); **Elizabeth Liebert**, Menlo Park, CA (US); **Judy M. Lee**, San Francisco, CA (US)

(73) Assignee: **The Iams Company**, Dayton, OH (US)

(**) Term: **14 Years**

(21) Appl. No.: **29/258,683**

(22) Filed: **Apr. 25, 2006**

(51) LOC (8) Cl. **02-06**

(52) U.S. Cl. **D2/617**

(58) Field of Classification Search **D29/113, D29/116, 116.3, 117.1, 117.2, 123; D2/610, D2/616-621, 623; D24/190; 2/4, 455, 16, 2/19-20, 162, 165-167, 159-160, 161.1, 2/161.2, 161.3, 161.4, 161.5, 161.6, 161.7, 2/161.8, 908, 917; D32/43; D30/158; D28/63**

See application file for complete search history.
